CLAIM

The ornamental design for a display screen with icon, as shown and described.

DESCRIPTION

FIG. 1 is a front view of a first embodiment display screen with icon showing my new design; and, FIG. 2 is a front view of a second embodiment thereof. The broken lines showing a portion of a display screen are for the purpose of illustrating environmental structure and form no part of the claimed design.

1 Claim, 2 Drawing Sheets

FIG. 1

FIG. 2
